UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

ROCK DRILL.

Application filed June 2, 1927. Serial No. 196,108.

This invention relates to rock drills and more particularly to a hole blowing device for fluid actuated rock drills of the hammer type.

5 An object of this invention is to provide an improved hole blowing device for rock drills. Another object is to provide an improved hole blowing device for fluid actuated rock drills of the hammer type whereby 10 the fluid distribution valve is held immovable to effect a hole blowing operation. Still another object of this invention is to admit an uninterrupted supply of pressure fluid to the drill steel for cleansing the drill hole and 15 to hold the distribution valve and hammer piston immovable while said pressure fluid is flowing through the drill steel. A further object is to provide an improved hole blowing device for a fluid actuated rock drill 20 wherein the automatic fluid distribution valve is pneumatically held in position to effect a hole blowing operation. These and other objects and advantages of this invention will, however, subsequently more fully appear.

25 In the accompanying drawing there is shown for purposes of illustration two forms which the invention may assume in practice.

In this drawing,—

Fig. 1 is a central, longitudinally extending, vertical sectional view through a rock drill embodying the improved hole blowing device, the parts being shown in position to effect a hole blowing operation.

Fig. 2 is a detail sectional view similar to 35 that shown in Fig. 1, showing the parts in a different position.

Fig. 3 is a detail sectional view illustrating a slightly modified form of construction.

In this illustrative construction there is 40 shown a rock drill of the pressure fluid actuated impact type comprising a cylinder 1 having a bore 2 in which a hammer piston 3 is reciprocably mounted. The hammer piston 3 is provided with a forwardly projecting 45 striking bar 4 movably mounted within a bore 5 formed within the usual front cylinder head 6 and this striking bar is adapted to impart a series of blows on the shank of a hollow drill steel 7. The drill steel 7 is 50 loosely mounted in a usual manner within a chuck bushing 8 secured to a chuck sleeve 9 rotatably mounted within a usual chuck housing 10. As illustrated, the rear end of the cylinder bore is closed by a washer 11 55 while interposed between this washer and

a rear head member 12 is a usual ratchet ring 13. The chuck housing 10 and front cylinder head 6, cylinder 1, rear washer 11, the rear head 12 and the ratchet ring 13 are held together in a suitable and convenient manner. 60 for instance by usual side bolts or rods (not shown).

In order to impart a rotary movement to the hammer piston 3 during one of its strokes, preferably during the rearward stroke, for 65 rotating the drill steel 7, a spirally grooved rifle bar 14 extends through the washer 11 to engage the hammer piston 3 in the usual manner. The means for holding the rifle bar 14 immovable during one stroke of the piston 70 and for permitting rotation of the rifle bar during the opposite stroke of the piston consists of a usual ratchet and pawl device generally designated 15. Rotary movement of the piston is transmitted to the drill steel 75 by means of straight flutes 16 formed on the periphery of the striking bar 4. The flutes 16 engage straight lugs 17 formed on a chuck nut 18 secured to the rotatable chuck 80 sleeve 9.

Herein preferably formed integral with the cylinder 1, is a valve chest 19 in which a valve chamber 20 is formed to receive an automatic fluid distributing valve 21. The fluid distributing valve 21 may be of any 85 suitable type as the invention is not dependent upon the particular valve illustrated or its successful functioning and the invention may be used in connection with any type of valve which controls both the admission of 90 pressure fluid to the cylinder and the exhaust of pressure fluid therefrom. The valve 21 in this instance is of the well known three-spool differential type having an enlarged central spool 22 and reduced end 95 spools 23. The central spool 22 controls the admission of pressure fluid through an inlet 24 into the valve chamber 20 and the end spools 23 have opposed actuating faces 25 and 25a respectively against which pressure fluid 100 may act for moving the distribution valve from one extreme position to the other. The end spools 23 also control free exhaust ports 26 and 27 respectively leading from the valve chamber 20 to atmosphere. Pressure fluid admitted into the chamber 20 may pass to the rearward and front ends of the cylinder bore 2 through supply passages 28 and 29 respectively. In this instance the supply passages 28 and 29 also serve as exhaust passages for 105 110

exhausting the pressure fluid from the cylinder. Suitable buffer plugs 30 and 31 are provided for limiting movement of the valve in opposite directions.

5 Usually in rock drills employing the type of valve herein described, throwing passages are employed for admitting pressure fluid from the cylinder to act against the actuating faces of the valve. Such throwing passages may be crossed as in the present instance in which a throwing passage 32 leads from the front end of the cylinder bore 2 to the rearward end of the valve chamber 20 and is controlled by the hammer piston 3. 10 A second piston controlled throwing passage 33 leads from the rear end of the cylinder bore 2 to the front end of the valve chamber 20. 15 The improved hole blowing device comprises a reciprocable plunger valve 34 extending through a central bore 35 in the distribution valve 21 and slidably mounted in bores 36 and 37 formed in the buffer plugs 30 and 31 respectively. The plunger valve 34 is externally grooved at 38 and 39 at points 20 spaced longitudinally thereof and is provided at its forward end with a conveniently located push button 40. As shown, the buffer plug 30 has formed therein radial ports 41 connecting the bore 36 with the valve chamber at the rear end of the valve 21. Also formed in the buffer plug 30 and adjacent portions of the valve chest are radial ports 42 which connect the bore 36 with the atmosphere. The buffer plug 31 is provided with 25 radial ports 43 which connect the bore 37 with the valve chamber at the forward end of the valve 21 and is also provided with radial ports 44 which connect the bore 37 with an annular groove 45. The groove 45 is connected through a passage 46 with the pressure fluid inlet 24. In this instance, the plunger valve 34 is held in its released or inoperative position as shown in Fig. 2 by means of a coiled spring 47 seated within a bore 48 30 formed in the buffer plug 31 and engaging a transverse pin 49 carried by the valve 34. As illustrated, the valve 34 has formed centrally therein restricted vent passages 50 and 51 which connect the valve chamber at the opposite ends of the valve 21 to atmosphere when the plunger valve 34 is in its released position as shown in Fig. 2.

In the modification shown in Fig. 3, the structure is generally the same as that described above in Figs. 1 and 2 with the exception that the push button 40 and the spring 47 for holding the valve in its released position are located at the rear end of the valve 21. This arrangement permits the plunger valve 34 to be operated from the rear end of the drill by simply sliding the valve forwardly to effect a hole blowing operation. In view of the fact that the valve is to be operated in the reverse direction from that shown in Figs. 1 and 2, the location of annular

grooves 38 and 39 relative to passages in the buffer plugs is changed correspondingly so as to establish communication between ports 41 and 42 and between ports 43 and 44 upon a forward movement of the valve, 70 and to cut off such communication in the normal rearward position of the valve.

In the normal operation of the rock drill, pressure fluid flows through inlet passage 24 and when the distribution valve 21 is in the position shown in Fig. 2 fluid flows past the rear surface of the central spool 22 and through the passage 28 to the rear end of the cylinder bore 2 where it acts on the rear surface of the piston 3 and moves the latter forwardly to strike a blow on the drill steel 7. The exhaust fluid from the forward end of the cylinder bore flows through the passage 29 past the rear surface of the front end spool of the distribution valve 21 and through 80 the exhaust passage 27 to atmosphere. The distribution valve 21 is held in its forward position by reason of the larger effective area of the central spool. When the hammer piston uncovers the throwing passage 33, pressure fluid is admitted from the rear end of the cylinder bore to the forward end of the valve 21 and consequently the latter is thrown rearwardly to the position shown in Fig. 1. Pressure fluid now enters the forward end of the cylinder bore through inlet passage 24, past the forward surface of the central spool 22 on the valve and through the passage 29 and consequently the hammer piston is moved rearwardly. The exhaust now 90 takes place through passage 28 past the forward surface of the rear spool 23 of the distribution valve and through the exhaust passage 26 to atmosphere. The restricted vent passages 50 and 51 in the plunger valve 34 prevent any back pressure from building up in the valve chamber at the opposite ends of the distribution valve and as a result, the valve action is materially quickened. As soon as the piston 3 has uncovered the throwing 100 passage 32, the distribution valve 21 is again shifted to its forward position and this cycle continues during the normal operation of the drill.

When it is desired to effect a hole blowing operation, the operator presses against the push button 40 and moves the plunger valve 34 rearwardly from the position shown in Fig. 2 to the position shown in Fig. 1. When the plunger valve 34 is in the position shown 110 in Fig. 1, the groove 38 connects the radial ports 41 and 42 and consequently the valve chamber at the rear end of the valve 21 is vented to atmosphere. Simultaneously the groove 39 connects the radial ports 43 and 44 and consequently live pressure fluid is admitted from the inlet 24 through passage 46 and groove 45 to the valve chamber at the forward end of the valve. Resultantly, the throwing pressure acting on the actuating 120

- face 25 of the valve is relieved and at the same time a pressure is built up against the actuating face 25^a on the valve 21, shifting the valve 21 to its extreme rearward position 5 and pneumatically holding the same immovable. When the valve 21 is held in its retracted position as shown in Fig. 1, pressure fluid flows from the inlet 24 past the forward surface of the central spool 22 of the distribution valve and through the passage 29 to the forward end of the cylinder bore. The continuous pressure flowing to this end of the cylinder bore forces the piston 3 rearwardly against the rear cylinder washer 11 and consequently pressure fluid flows from the cylinder bore through the flutes 16 on the striking bar 4, through the chuck nut 18, and thence through the bore in the drill steel to the bottom of the drill hole. As soon as the manual 10 pressure on the push button 40 is released, the plunger valve 34 is automatically returned to its inoperative position and the distribution valve 21 will then resume its normal operation and the drill will again function in a normal manner. The operation of the modification shown in Fig. 3 is substantially the same as that described above with the exception that the plunger valve is moved forwardly to vent the rear end of the valve chamber 20 to atmosphere and to supply live fluid to the front end of the valve chamber. These and other uses and advantages of this invention will be clearly apparent to those skilled in this art.
- 35 While I have in this application specifically described two forms which my invention may assume in practice, it will be understood that these forms of the same are shown for purposes of illustration and that the invention may be modified and embodied in various other forms without departing from its spirit or the scope of the appended claims.
- What I claim as new and desire to secure by Letters Patent is:
- 45 1. In a fluid actuated rock drill of the hammer type, the combination of a cylinder and a piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, and a hole blowing device comprising a member arranged coaxially with said fluid distributing valve, valve means controlled by movement thereof for admitting pressure fluid to one valve chest space and valve means also controlled by movement of said member for venting the opposed space to atmosphere whereby said distributing valve is pneumatically held immovable to effect a hole blowing operation.
- 55 2. In a fluid actuated rock drill of the hammer type, the combination of a cylinder and a piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, and a hole blowing device comprising a manually operable reciprocable plunger valve arranged coaxially with said distributing valve having fluid conducting means for admitting pressure fluid to
- and a fluid distributing valve therein controlling both the supply and exhaust of pressure fluid for said cylinder, valve throwing passages between opposed spaces in the valve chest and the cylinder bore for supplying pressure fluid for actuating said valve, and a hole blowing device comprising a member arranged coaxially with said fluid distributing valve and extending therethrough, means carried by said member for admitting pressure fluid to one valve chest space and means controlled by movement of said member for venting the opposed space to atmosphere whereby said distributing valve is pneumatically held immovable to effect a hole blowing operation.
3. In a fluid actuated rock drill of the hammer type, the combination of a cylinder and a piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, and a hole blowing device comprising an auxiliary valve arranged coaxially with said fluid distributing valve having fluid conducting means for admitting pressure fluid to one valve chest space and also having fluid conducting means for venting the opposed space to atmosphere whereby said distributing valve is pneumatically held immovable to effect a hole blowing operation.
4. In a fluid actuated rock drill of the hammer type, the combination of a cylinder and a piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, and a hole blowing device comprising an auxiliary valve arranged coaxially with said fluid distributing valve and extending therethrough and having fluid conducting means adjacent one end for admitting pressure fluid to one valve chest space and fluid conducting means for venting the opposed space to atmosphere whereby said distributing valve is pneumatically held immovable to effect a hole blowing operation.
5. In a fluid actuated rock drill of the hammer type, the combination of a cylinder and a piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, and a hole blowing device comprising a manually operable reciprocable plunger valve arranged coaxially with said distributing valve having fluid conducting means for admitting pressure fluid to

one valve chest space and also having fluid conducting means for venting the opposed space to atmosphere whereby said distributing valve is pneumatically held immovable to effect a hole blowing operation.

6. In a fluid actuated rock drill of the hammer type, the combination of a cylinder and a piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, and a hole blowing device comprising an auxiliary pressure fluid supply means for one of said valve chest spaces and auxiliary venting means for the other valve chest space, and an auxiliary valve arranged coaxially with said distribution valve having means for controlling opening of said auxiliary pressure fluid supply means and also having means for opening said venting means whereby said fluid distributing valve is pneumatically held immovable to effect a hole blowing operation.

7. In a fluid actuated rock drill of the hammer type, the combination of a cylinder and a piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, a hole blowing device comprising means for admitting pressure fluid to one valve chest space and means for venting the opposed space to atmosphere whereby said distributing valve is pneumatically held immovable to effect a hole blowing operation, and means provided by said hole blowing device for venting said valve chest spaces to atmosphere during normal operation of said distributing valve.

8. In a fluid actuated rock drill of the hammer type, the combination of a cylinder and a piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, a hole blowing device comprising a manually operable plunger valve arranged coaxially with said distributing valve for admitting pressure fluid to one valve chest space and for venting the opposed space to atmosphere whereby said distributing valve is pneumatically held immovable to effect a hole blowing operation, and means associated with said plunger valve including vent passages formed therein for venting said opposed valve chest spaces to atmosphere during normal operation of said distributing valve and when said plunger valve is in its released position.

9. In a fluid actuated rock drill of the hammer type, the combination of a cylinder and a piston reciprocable therein, a valve chest, a fluid distributing valve therein controlling both the supply and exhaust of pressure fluid for said cylinder, buffer plugs for limiting movement of said valve in opposite directions, said buffer plugs having central bores and ports in said plugs for respectively connecting opposed spaces in said valve chest to a supplemental source of fluid supply and to atmosphere, valve throwing passages between said opposed spaces in the valve chest and the cylinder bore for supplying pressure fluid for actuating said valve, and a hole blowing device comprising a manually operable plunger valve arranged coaxially with said distribution valve and slidably mounted in the bores in said plugs, said valve having means for connecting said ports in said plugs respectively to said supplemental source of supply and to atmosphere on movement of said valve whereby said distribution valve is pneumatically held immovable to effect a hole blowing operation.

10. In a fluid actuated rock drill of the hammer type, the combination of a cylinder and a piston reciprocable therein, and fluid distribution means including supply and exhaust passages for said cylinder, a valve chest, a fluid distributing valve therein controlling said passages, and valve throwing passages for connecting opposed spaces in said valve chest with the cylinder bore for supplying pressure fluid for actuating said valve, means for blowing a drilled hole comprising auxiliary supply passages for admitting pressure fluid to one of said valve chest spaces, and passages for venting the other space to atmosphere whereby said distributing valve is pneumatically held immovable to effect a hole blowing operation, said auxiliary supply passage and said vent passages being separate and distinct from said distribution passages and said valve throwing passages, and a manually operable valve for controlling said auxiliary supply passages and said venting passages.

11. In a fluid actuated rock drill of the hammer type, the combination of a cylinder and a piston reciprocable therein, a valve chest having a fluid distributing valve therein, controlling both the supply and exhaust of pressure fluid for said cylinder, valve throwing passages between opposed spaces in the valve chest and the cylinder bore for supplying pressure fluid for actuating said valve, and a hole blowing device comprising a manually controlled reciprocable element extending through said distribution valve, means controlled by movement of said element for applying a force to shift and hold said valve in one position for effecting a hole blowing operation, and means controlled by movement of said element for relieving the pressure on

an area of said valve tending to oppose said shifting thereof.

12. In a fluid actuated rock drill of the hammer type, the combination of a cylinder 5 and a piston reciprocable therein, a valve chest and a fluid distributing valve therein controlling both the supply and exhaust of pressure fluid for said cylinder, valve throwing passages between opposed spaces in the 10 valve chest and the cylinder bore for supplying pressure fluid for actuating said valve, and a hole blowing device including means for venting the space at one end of the valve to atmosphere, said means including an element extending through said valve and manually operable from the opposite end of the valve.

13. In a fluid actuated rock drill of the hammer type, the combination of a cylinder 20 and a piston reciprocable therein, a valve chest and a fluid distributing valve therein controlling both the supply and exhaust of pressure fluid for said cylinder, valve throwing 25 passages between opposed spaces in the valve chest and the cylinder bore for supplying pressure fluid for actuating said valve, means including an auxiliary valve for vent-

ing the valve chest space at one end of said valve to atmosphere during a hole blowing operation, and means for venting said valve 30 chest spaces to atmosphere during normal operation of said fluid distribution valve including vent means formed in said auxiliary valve.

14. In a fluid actuated rock drill of the hammer type, the combination of a cylinder 35 and a piston reciprocable therein, a valve chest and a fluid distributing valve therein controlling both the supply and exhaust of pressure fluid for said cylinder, valve throwing 40 passages between opposed spaces in said valve chest and the cylinder bore for supplying pressure fluid for actuating said valve, and a hole blowing device including an auxiliary valve arranged coaxially with and extending through said distributing valve manually operable from the forward end of said distributing valve for venting the valve chest space at the rear end of said distributing 45 valve to atmosphere during a hole blowing 50 operation.

In testimony whereof I affix my signature.

CHARLES F. OSGOOD.
